ATTORNEY

UNITED STATES PATENT OFFICE.

SAMUEL SAMPSON, OF NEW YORK, N. Y.

DESIGN FOR A COLLAR-HOLDER.

55,488.

Specification for Design. Patented June 15, 1920.

Application filed March 31, 1920. Serial No. 370,345. Term of patent 14 years.

To all whom it may concern:

Be it known that I, SAMUEL SAMPSON, a citizen of the United States, residing at New York city, borough of Manhattan, in the county and State of New York, have invented a new, original, and ornamental Design for a Collar-Holder, of which the following is a specification, reference being had to the accompanying drawings, forming part thereof.

Drawings.

Fig. 2 is an edge view of the same.

I claim:

The ornamental design for a collar holder, as shown.

SAMUEL SAMPSON.
